UNITED STATES PATENT OFFICE.

NATHAN M. LOWER, OF PITTSBURGH, PENNSYLVANIA, ASSIGNEE TO LOCOMOTIVE STOKER COMPANY, A CORPORATION OF PENNSYLVANIA.

FUEL CONVEYING AND CRUSHING MECHANISM.

1,384,138.

Specification of Letters Patent. Patented July 12, 1921.

Application filed November 25, 1919. Serial No. 340,496.

To all whom it may concern:

Be it known that I, NATHAN M. LOWER, a citizen of the United States, and resident of Pittsburgh, county of Allegheny, and State of Pennsylvania, have invented certain new and useful Improvements in Fuel Conveying and Crushing Mechanism, of which the following is a specification, and which are illustrated in the accompanying drawings, forming a part thereof.

The invention relates to mechanism for conveying fuel, as from a locomotive tender, to a locomotive fire-box, and for reducing the larger lumps to a suitable size while being so conveyed.

The invention consists of a conduit, a fuel-advancing device, such as a spiral conveyer, and one or more rigid bands or straps secured within the conduit and partially encircling the conveyer.

In the accompanying drawings illustrating the invention—

Figure 1 is a transverse section through the conduit and conveyer and a portion of the floor of the bin, a pair of crushing straps being shown in elevation;

Fig. 2 is a detail longitudinal vertical section of the device as shown in Fig. 1;

Fig. 3 is a view similar to Fig. 1, showing a modified form of construction;

Fig. 4 is a detail longitudinal vertical section of the construction shown in Fig. 3; and

Fig. 5 is a sectional view on the line 5—5 of Fig. 4.

The invention is intended especially for use in connection with locomotive stokers. The floor of the locomotive tender is represented at 10, and is provided with an opening for the discharge of the fuel therethrough, this opening being guarded by a depending flange 11. A trough 12, located below the floor of the tender, receives fuel through the opening in the floor 10. Fuel-advancing means is provided within the trough 12, and preferably takes the form of a spiral conveyer 13, as shown.

It is common practice to use "run of mine" coal on locomotives, and consequently there frequently occur lumps of coal which are larger than can be conveniently delivered through the stoker mechanism and of greater size than it is desirable to introduce

into the fire-box, and hence it becomes necessary to provide means for reducing these large pieces. In the present invention the fuel-crushing mechanism consists of a heavy metal band or strap, as 14, arching over and substantially concentric with the spiral conveyer 13, its inner face being preferably approximately parallel with the axis thereof. This strap is firmly and rigidly secured to the trough 12 by having its end portions 15, 16, bent to conform to the side walls of the trough and being attached thereto, as by means of rivets.

Preferably a plurality of such crushing bands are employed, there being two shown in the drawings,—the band 17, which is first encountered by the advancing fuel, being of the larger radius. The band 17 may be secured within the trough in the same manner as the band 14. As the fuel is advanced lumps which are too large to pass under the band 17 are crushed against its edge by the pressure of the conveyer vane, and thus partially reduced in size. Such of the lumps, or fragments of the larger lumps, as pass under the band 17, but are of a size too large to pass under the band 14, are similarly crushed against the edge of the latter.

By employing a plurality of crushing bands the stresses incident to the crushing action are distributed and congestion of the fuel is avoided. These advantages may be secured to even a greater extent by using more than two crushing bands, and this would be particularly desirable where fuel is supplied containing exceedingly large lumps.

The modification of Figs. 3 to 5 differs essentially from the form shown in Figs. 1 and 2 only in the construction of the parts. The smaller crushing band 18 is an integral part of a casting 19 which forms a section of the trough, the larger crushing band 20 being secured within the trough and, as shown, partly to the casting 19 and partly to the rearward section 21 of the trough, which is usually of heavy plate.

In the construction of Figs. 1 and 2 there is provided a reinforcing shoe 22, located in the bottom of the trough 12 below the crushing bands, its purpose being to prevent an undue deflection of the conveyer shaft in the crushing operation.

In the construction of Figs. 3 to 5, the bottom of the casing 19 is offset upwardly, thereby providing a similar reinforcement.

I claim as my invention—

- 5 1. In a fuel conveyer and crusher, in combination, a conduit, fuel advancing means within the conduit, and a crushing abutment arching over the advancing means and co-acting therewith, such abutment being in the form of a plate having its inner face parallel with the axis of the conduit.
- 10 2. In a fuel conveyer and crusher, in combination, a conduit, fuel-advancing means within the conduit, and a crushing abutment arching over the advancing means and co-acting therewith, such abutment being in the form of a plate having its inner face parallel with the axis of the conduit, the conduit having a receiving opening adapted to admit 20 pieces of fuel larger than the capacity of the conduit.
- 15 3. In a fuel conveyer and crusher, a casting formed on in arc and adapted to serve as a section of a conduit, a shoulder at each end 25 of said arc, each shoulder adapted to support an end of a section of conduit, a second arc integral at its ends with the first-named arc and of reverse curvature, said second-named arc adapted to serve as a crusher, 30 and a spiral conveyer inclosed within such arcs.
- 20 4. In a fuel conveyer and crusher, in combination, a conduit, a screw conveyer within the conduit, and a crushing abutment in the 35 form of a plate arching over the screw conveyer, the concave face of the plate being parallel with the axis of the conduit.
- 40 5. In a fuel conveyer and crusher, in combination, a conduit, fuel advancing means within the conduit, and a plurality of crushing abutments crossing the conduit above the advancing means, spaced differently therefrom, and from each other axially of the conduit.
- 45 6. In a fuel conveyer and crusher, in combination, a conduit, a screw conveyer in the conduit, and a plurality of crushing abutments arching over the screw, differently spaced therefrom, and spaced from each other axially of the conduit.
- 50 7. In a fuel conveyer and crusher, in combination, a conduit, fuel advancing means within the conduit, and a plurality of bars in strap form arching over the advancing means at different axial locations and differently spaced therefrom.
- 55 8. In a fuel conveyer and crusher, in combination, a conduit, fuel-advancing means within the conduit, a plurality of bars arching over the advancing means spaced from each other axially of said means, the diameters of successive arches being less in the direction of advance by action of said means.
- 60 9. In a fuel conveyer and crusher, in combination, a conduit, fuel-advancing means in 65 said conduit, crushing means comprising a succession of cylindrical surfaces arching over said advancing means, successive surfaces in the direction of fuel advance being of less diameter than its predecessor, the 70 rearward end of each surface presenting a crushing shoulder to the advancing fuel.

NATHAN M. LOWER.
